SHIPPING CONTAINER

Oscar W. Meller, Akron, Edsel F. Moffitt, Tallmadge, and Frank C. Morse and Gerald L. Woodling, Akron, Ohio, assignors to Goodyear Aerospace Corporation, Akron, Ohio, a corporation of Delaware

Filed Nov. 29, 1968, Ser. No. 14,718

Term of patent 14 years

Int. Cl. D9—05

U.S. Cl. D9—246

FIG.-1

FIG.-2

FIG. - 3

FIG. - 4

FIG. - 5

FIG. 1 is a perspective view of the shipping container showing one form of our design wherein fabric material forms the full front and rear closures of the container;

FIG. 2 is a perspective view of the shipping container showing a second form of our design wherein foldable doors form full front and rear closures of the container;

FIG. 3 is a perspective view of the shipping container showing a third form of our design wherein fabric and corrugated panels are combined to form partial front and rear closures of the container;

FIG. 4 is a perspective view of the shipping container showing a fourth form of our design wherein fabric material forms partial front and rear closures of the container; and

FIG. 5 is a perspective view of the shipping container showing a fifth form of our design wherein foldable doors form partial front and rear closures of the container.

The base of our new design for a shipping container is a smooth plane panel and the top and sides are matched corrugated panels.

We claim:

The ornamental design for a shipping container, as shown and described.
